UNITED STATES PATENT OFFICE.

GEORGE H. GILMAN, OF BOSTON, MASSACHUSETTS.

DRILLING MACHINE.

Application filed November 4, 1920. Serial No. 421,748.

My invention relates to drilling machines and more particularly but not exclusively to those for drilling rock and operated by fluids under pressure.

5 My invention will be best understood from the following description when read in the light of the accompanying drawings of one specific embodiment of my invention selected for illustrative purposes, while the scope of 10 my invention will be more particularly pointed out in the appended claims.

In the drawings:

Figure 1 shows a longitudinal section of the submitted embodiment of my invention, 15 parts being broken away;

Fig. 2 is a section on the line 2—2 of Fig. 1;

Figs. 3 and 4 are sections respectively on the lines 3—3 and 4—4 of Fig. 2;

20 Figs. 5, 6, 7 and 8 are respectively sections on the lines 5—5, 6—6, 7—7 and 8—8 of Fig. 1;

Figs. 9 and 10 are respectively sections on the lines 9—9 and 10—10 of Fig. 2;

25 Fig. 11 is a plan view of the carriage for adapting the drilling mechanism to the cradle of the feed mechanism;

Fig. 12 is a section on the line 12—12 of Fig. 11;

30 Fig. 13 is an end elevation of Fig. 11;

Figs. 14 and 15 are diagrams illustrating the operation of the submitted embodiment of my invention;

35 Fig. 16 is a diagram showing some of the connections to the throttle valve; and

Figs. 17 and 18 are diagrams respectively illustrating the throttle valve in its "throttling" and "off" positions.

40 Referring more particularly to Figs. 1 to 10, the rock drill in the submitted embodiment of my invention comprises a drill steel 1 and mechanism for operating the same by imparting percussion thereto and rotating it.

45 For imparting percussion to the drill steel I have illustrated a piston having a body portion or head 2 of large diameter and projecting therefrom, a hammer bar 3, the front end of the latter being adapted to strike the rear end of the drill steel at the end of the forward stroke of the piston. As shown the piston is further provided with a rearward extension 4 of smaller diameter connected to the body portion 2 by means of the reduced diameter portion 5. Surrounding

the piston is a casing herein comprising a cylinder member 6 having a forward bore 7 of large diameter for the large diameter portion 2 of the piston and a rearward cylinder member having the bore 8 of smaller diameter for the small diameter portion of the piston.

50 As illustrated the rearward cylinder member comprises a block 9 forming a closure for the larger bore 7 and carried thereby a rearwardly extending member 10. The member 10 herein is provided with a flange 11 which abuts the rearward face of the block 9 and at its forward end is provided with a cylindrical portion 12 which enters the bore 13 of the block 9. For maintaining the extension 10 and block 9 in fixed angular relation I have shown the dowel 14, and for maintaining the same in assembled relation I have shown the end of the portion 12 as 55 upset into a counter-sunk portion at the forward end of the bore 13 as indicated at 15. Herein integrally formed with the extension 10 is a rear cylinder head 16.

50 The drill steel is carried by the chuck 16^a 80 in any suitable manner sufficient to cause rotative movement of the chuck to be imparted to the steel. Herein the chuck has an exterior bearing 17 in the chuck casing 18 and at its rearward end an exterior bearing 19 in the front cylinder head 20. On the exterior portion of the chuck intermediate the bearings are illustrated gear teeth 21 and meshing therewith the internal gear teeth of the yokes 22. These yokes operate 85 to form a reduction gearing and for driving the same I have shown a rotary motor comprising the intermediate gear member 23 and the side gear members 24. Driven by the side gear members are the shafts 25, each 90 of which in the present embodiment of my invention carries a pair of eccentric members 26, which when the shafts are rotated act to gyrate the yokes and thus to rotate the drill steel. For connecting the shafts 95 25 to the rotors I have shown keys 25^a carried by the shafts entering suitable ways in the gear members 24. The keys are of such dimensions that the shafts may be drawn together with the keys through the 100 shaft bearing blocks 32 and 32^a. In general the details of the chuck rotating motor and gearing form no part of the invention to which this application is directed and therefore will not be described with more partic- 105

ularity than is necessary to show how they are applied to the invention under consideration.

The intermediate gear member 23 of the chuck rotating motor surrounds and is journalled on that portion of the cylinder extension 10 which is rearward of the block 9. For housing the operative parts of this motor I have shown a casing which comprises a lateral portion 27 and an end portion, the latter comprising for a purpose hereinafter to be described a sleeve 33 on the exterior surface of which is mounted the body 28 of the end casing. The sleeve 33 of the end casing is shown as provided with a flange 34 against which the forward portion of the body abuts, and for holding the parts in assembled relation the end of the sleeve is shown as upset into the counter-sunk portion of a body as is indicated at 35. For holding the motor and its casing in position I have shown a nut having the screw threaded portion 36 which enters the bore 37 formed in the rear cylinder head 16 and cooperates with screw threads formed on the interior portion of such bore. This nut is shown as provided with a flange 38 adapted to abut against the rearward face of the end portion of the chuck rotating motor casing when the nut is screwed into position.

As illustrated by Fig. 2 for supporting the intermediate portion of each shaft 25 I provide the anti-friction bearings 32 and 32^b respectively carried in suitable recesses in the block 9 and the front cylinder head 20. For supporting the ends of the shafts I have shown a rearward bearing in the block 32^b carried in a suitable recess in the motor casing member 28 and a forward bearing 32^a formed in the chuck casing. Herein the blocks 32 and 32^b respectively are formed with flanges 31 and 31^b, the flange 11 of the cylinder extension as illustrated by Fig. 9 being cut away to receive the flange 31, and the flange 31^b as illustrated by Fig. 10 being cut away to receive the flange 34 of the sleeve 33 of the motor casing. By this construction are provided smooth surfaces for the end faces of the motor gear members and a shoulder afforded by the edges of the respective flanges over which I fit the motor casing member 27 and thereby "dowel" the same to position it angularly. Further the bearing block 31 serves to position and "dowell" the extension 10 in its proper angular relation to the block 9; while the block 32^b, which carries the automatic lubricator hereinafter to be described, similarly positions and "dowels" the motor casing parts, 27, 28 and 33 to each other.

For holding the cylinder sections encasing the piston in assembled relation I have shown the side bolts 39. These side bolts preferably are of such number and are so arranged that two of them are located at

one side of a plane passing through the longitudinal axis of the machine, the purpose of which will be hereinafter described. These bolts I have shown provided with heads 40 engaging the chuck casing and nuts 41 70 engaging the rearward face of the chuck rotating motor casing. It will be observed that by removing the nuts 41, the sections of the cylinder may be separated and that the rearward portion of the cylinder together 75 with the chuck rotating motor may be removed as a unit.

I have shown the drilling machine as provided with a suitable feed mechanism which herein comprises the cradle 42 having the 80 ways 43, and the feed screw 44. Carried by the ways in slidable relation thereto is shown the carriage 45 provided with the guide members 46 cooperating with the ways on the cradle. The carriage herein is provided with upstanding members in the form of ears 47 which as shown are four in number. These ears are perforated as indicated at 48 to receive those side bolts 39 which are adjacent the carriage and herein the casing 90 is recessed as indicated at 49 and 50 to receive such ears. As indicated in Figs. 1, 5, 6, 7 and 8 the adjacent portions of the carriage and casing are finished to provide flat contacting surfaces for better holding the 95 parts in rigid assembled relation. It will be appreciated that by removing the two side bolts extending through the ears of the carriage the drilling machine may be removed from the carriage without disassembling the 100 drilling machine.

As hereinbefore described, in the present embodiment of my invention the portion 12 of the cylinder section encasing the rear piston extension is provided with a surface 105 which fits the bore 13 of the member 9 and likewise the exterior surface of the sleeve 33 fits the interior surface of the body portion of the end casing and the motor. In these surfaces as illustrated by Figs. 1 and 2 are formed 110 annular grooves 51, 52, 53, 54 and 55. Herein the groove 51 forms an oil reservoir and the grooves 52 and 53 respectively form conduits for distributing the admission motive fluid and exhaust motive fluid to and from the chuck rotating motor while the grooves 54 and 55 form part of the fluid distributing passages for reciprocating the piston. As illustrated by Figs. 1 and 10, the motor is provided at the intersection of the bores 115 29 and 30 with the admission passages 57 and at the opposite intersection as illustrated by Figs. 5 and 9, with exhaust passages 56. For convenience of illustration, these passages are shown in Fig. 1 by dotted lines somewhat out of position, the true positions being indicated by Figs. 5, 9 and 10. The groove 52 is connected by means of a conduit 58 with the motive fluid inlet 59 and the groove 53 by means of the conduit 60 120 125 130

with the atmosphere in a manner herein afterwards to be described. The purpose of employing the annular grooves will be appreciated from the consideration of the 5 conduits admitting motive fluid to the motor. In this connection it will be observed that the supply conduit 58 is on the top of the machine while the conduits 57 are angularly positioned with reference thereto circumferentially around the axis of the machine. Hereinbefore in such constructions it has been usual to drill intersecting 10 passages in the wall of the cylinder which as understood by those skilled in the art necessitates the use of plugs to close the ends of the holes thus drilled and the forming of 15 bosses or thickened portions on the cylinder wall to provide material for drilling the passages. By the construction herein set forth, 20 the manifest disadvantages of the prior construction are avoided.

Referring to Figs. 1, 2, 3, 4 and 6, I have illustrated the groove 55 as connected to a motive fluid supply passage 61 and with the forward portion of the rearward bore by 25 means of oppositely disposed passages 62, while the groove 54 is shown as connected to the forward portion of the rearward bore by means of oppositely disposed passages 63 and to the forward end of the larger bore by 30 means of a plurality of passages 64, one of which is shown in Fig. 1 out of angular position for convenience of illustration but the true position of which is illustrated by 35 Figs. 3 and 6. Extending rearwardly from the passages 62 I have shown longitudinal grooves 65 formed in the interior surface of the smaller bore and terminating in the 40 plane of the passages 63. By this construction, when the piston is adjacent the rearward end of the stroke as illustrated by Figs. 1 and 14, the motive fluid admitted to the 45 groove 55 passes into the rearward end of the cylinder bore of large diameter through the passages 62 and the passage afforded by the reduced diameter portion 5 of the piston; and when the piston is in its forward position as shown by Figs. 2 and 15, the motive 50 fluid passes by way of the passages 62 and 65 from the groove 55 into the smaller piston bore, whence it finds its way into the forward end of the larger cylinder bore through the passages 63, the groove 54 and 55 passages 64. When the piston moves forwardly from its rearward position, the supply to the rearward end of the larger cylinder bore is interrupted and when it moves rearwardly from its forward position the supply into the rearward end of the smaller 60 bore and the forward end of the larger bore is interrupted.

In the present embodiment of my invention the motive fluid admitted at the end of the forward stroke into the rearward portion 65 of the smaller cylinder bore is cut off

when the piston in its rearward movement closes the ports 65 and after this the motive fluid by the continued rearward movement of the piston is trapped and compressed above its initial pressure. During the forward stroke the pressure of the motive fluid at the rear of the piston extension 4 materially increases the energy imparted to the piston and this aids in producing a heavier blow than if motive fluid at initial pressure 70 were utilized in the smaller bore for producing the forward stroke. 75

In the intermediate portion of the cylinder as illustrated by Figs. 1 and 6 I have shown a slot 66, which serves as a piston controlled exhaust port and as will be clearly understood by those skilled in the art, this port permits the motive fluid to be alternately exhausted from the opposite sides of the piston portion 2 when uncovered thereby during its reciprocations. Formed in the wall of the cylinder I have shown a pair of longitudinal passages 67 which intersect the slot 66 and are adapted to be placed in communication with the atmosphere in a 80 manner hereinafter described. 85

Besides the valveless fluid distributing features so far described I may also provide additional fluid distributing means in the form of a valve. As will be understood by those skilled in the art, the fluid distribution directly controlled by the piston, such usually being termed a "valveless distribution", has the advantage of quickly admitting and exhausting motive fluid, but has the disadvantage that an early point of 90 cut-off and compression must be provided. On the other hand, when the fluid distribution is controlled solely by a valve these advantages and disadvantages are reversed. 95 By properly combining the two forms of distribution, the disadvantages of each may be eliminated and the advantages of both retained, which is to say that by means of the valveless distribution the quick admission 100 and release may be obtained and by means of the valve the mean effective pressure may be increased by making the effective point of cut-off and compression late in the stroke. 105 The valve in the submitted embodiment of 110 my invention controls admission and exhaust of fluid to both sides of the piston portion for both its strokes, although as will be obvious, the admission or exhaust events controlled by the valve for the fluid used 115 at either side of the piston portion 2, may be omitted. It may, however, be pointed out, that owing to the compression of the fluid in the chamber 8 on the rearward stroke, either or both a late point of compression for the 120 fluid exhausted at the rear of the piston portion 2 and late point of cut-off for that admitted in front of this piston portion is desirable. This application is not concerned 125 with the details of the valve and therefore 130

only so much of it as necessary for a clear understanding of my present invention will be described.

As shown, the cylinder is provided with a longitudinally arranged lateral enlargement 68 which receives the valve cage sections 69 and 70 for housing the tubular valve 71 more fully described. The internal bore of the valve cage is provided with a conduit 72 adapted in a manner hereinafter described, to be placed in connection with the source of motive fluid supply and is also provided with the annular grooves 73, 74, 75, 76 and 77. The exterior surface of the valve is provided with the circumferentially arranged flange 78 and the grooves 79 and 80. The annular grooves 74 and 76 just referred to are connected by means of passages 81 and 82 with the exhaust passages 67, while the grooves 73 and 77 respectively are connected by means of passages 83 and 84 with the cylinder bore of larger diameter adjacent its opposite ends. The flange 78 of the valve fits in a fluid tight manner the interior surface of the annular groove 75 of the valve casing and extending from opposite ends of the groove 75 to the interior of the enlarged bore of the cylinder are the crossed kicker passages 85 and 86. As will be understood by those skilled in the art, when the piston reciprocates, motive fluid is alternately admitted and exhausted by means of the kicker passages 85 and 86 to the annular groove 75 of the valve casing to act upon the flange 78 of the valve to cause the valve to be thrown to opposite ends of its travel.

The operation of the parts described for controlling the fluid causing the piston to reciprocate is as follows:

When the piston is in the rearward portion of its stroke as illustrated by Fig. 14, the valve has been moved by the fluid admitted by the kicker port 86 to the forward end of its travel. In this position of the parts, assuming the motive fluid is admitted through the passages 61 and 72 respectively to the groove 55 and to the interior of the valve, motive fluid will flow from the groove 55 by way of the passages 62 and around the reduced portion 5 of the piston into the rear of the larger cylinder bore and when the piston portion 2 uncovers the passage 83 leading from the valve cage, motive fluid will be admitted from the passage 72 by way of the groove 73 and passage 83 into the rearward end of the cylinder portion of large diameter. In this position of the parts, the piston has uncovered the exhaust slot 66 which permits the motive fluid in front of the piston to exhaust through said slot into the passage 67 whence it finds its way to the atmosphere. Also motive fluid in front of the piston may pass through the passage 84, the groove 77 of the valve cage,

the groove 80 of the valve, the groove 76 of the valve cage, and the passage 82 into the exhaust passages 67.

When the piston reaches the forward end of its stroke as illustrated by Fig. 15, the valve has been thrown to the rearward end of its travel by means of motive fluid admitted through the kicker passage 85. After the piston moves backward owing to its rebound far enough to uncover the forward end of the passages 64 and the passage 84, motive fluid is admitted to the forward end of the cylinder bore of large diameter from the groove 55 by way of the passages 62, groove 65, passages 63, annular groove 54 and passages 64 and likewise from the passage 72 through the interior of the valve, the groove 77 in the valve cage and the passage 84. As the piston moves rearwardly, the motive fluid in front of the enlarged piston portion 2 passes through the slot 66, to the passages 67 whence it finds its way to the atmosphere. Motive fluid as the piston moves rearwardly, also exhausts into the passages 67 by way of the passage 83, groove 73 in the valve cage, groove 79 in the valve, groove 74 in the valve cage and passages 81. At the end of the forward stroke, when the cylinder bore of smaller diameter has been expanded by the piston, the chamber formed thereby is filled with live motive fluid which passes from the groove 55 thereto by way of the passages 62 and 65 and when during the rearward stroke, the passage 65 is closed, this motive fluid is trapped between the rearward end of the piston portion of smaller diameter and the rear cylinder head, which compresses the fluid to a high degree of pressure when the piston reaches the rearward end of its stroke. The energy thus stored up in the compressed motive fluid is available for imparting to the piston a greater momentum on its forward stroke than if motive fluid at initial pressure were used in the rear piston chamber of smaller diameter.

Motive fluid is led to the machine through a suitable air hose connection shown at 87 which conducts motive fluid to the intake 59. For controlling the motive fluid I may use any suitable valvular mechanism, as for example the valve illustrated by Figs. 1, 14, 15, 16, 17 and 18. This valve is in its general aspects of the usual "turning-plug" type. Formed in the valve is a longitudinal passage 88 and communicating therewith the radial passages 89, 90 and 91. In the full open operating position of the valve as illustrated by Figs. 1 and 14 the passage 89 is in communication with the motive fluid supply connection 59, which delivers motive fluid to the passage 92 leading to the valve cage conduit 72 and to the passage 61 leading to the groove 55. Through the wall of the portion of the block 9 constituting the throttle valve casing are passages 93 in commu-

nication with the atmosphere and a pair of passages 94 in communication with the exhaust passages 67. In the operating position of the valve, the communication is established between the passages 94 and 93 by means of the exterior recesses 95, formed in the valve. On the exterior portion of the valve in communication with one of the recesses 95 is an arcuate slot 96 which in all positions of the valve is adapted to be in communication with the passage 60 conducting exhaust motive fluid from the chuck rotating motor. This motor is supplied with motive fluid through the connection 97, which communicates with the intake connection 59 in advance of the throttle valve and in this manner the motive fluid is always admitted to and exhausted from the chuck rotating motor irrespective of the position of the throttle valve. For controlling the chuck rotating motor I may provide a suitable throttle valve 98 carried by the chuck rotating motor casing.

For conducting water to the drill bit, I have shown a water tube 99 which herein communicates with the bore 100 of the bit and is supported at its rearward end in the rear cylinder head 16. For securing the water tube and forming a water tight joint at the rear head, I have shown a packing 101 of rubber or the like which is positioned in the cavity 37 of the rear head and surrounds the rearward end of the water tube. When the nut 36 is screwed into position the packing 101 is compressed and thus securely clamps and packs the rearward end of the tube. Herein the nut is provided with a passage 102 which at its rearward end is enlarged and provided with securing means for the water hose connection 103.

For supplying the bit with air, I have shown a passage 104, shown in Figs. 1, 7, 14 and 15, in communication with one of the exhaust passages 67 or if desired I may provide two passages 104, each in communication with one of the passages 67. For supplying the passage 104 with air to blow the hole, I have shown the throttle valve as provided with a passage 105 in communication with the interior conduit 88 of the valve. Herein this passage 105 terminates on the exterior of the valve in the same plane as one of the passages 67 so that when the valve is turned to interrupt communication between the exhaust discharge 93 and the exhaust passage 67, the passage 105 will be brought into communication with the passage 67 and therefore fill the interior of the machine with live air which finds its way through the passages 67 and 104 to the interior of the chuck chamber and hence into the bore of the drill steel.

The operation of my throttle valve will be best understood from Figs. 14, 15, 16, 17 and 18. Fig. 16 shows a plan of the valve

corresponding with the section shown in Fig. 1, with some of the connecting passages shown diagrammatically by dotted lines. In Figs. 14, 15, 17 and 18, the valve is represented by three sections respectively on the lines *a-a*, *b-b*, *c-c* of Fig. 16. Fig. 14 shows the full open running position, Fig. 15 the hole blowing position, Fig. 18 the throttling position and Fig. 17 the "off" or inoperative position.

In the position of the parts, illustrated by Fig. 14, the motive fluid is admitted from the intake connection 59 through the throttle valve to the passages 92 and 61 to the valve and valveless distributing means of the percussive mechanism, while the exhaust from the same is conducted from the passages 67 through the exterior slots 95 of the valve to the exhaust discharge 93. In this position the passage 105 is blanked and therefore the hole is not blown and the piston reciprocates. Motive fluid is led through the passage 97 from the intake connection 59 and passes, if the valve 98 is open, into the groove 52 whence it is distributed by the passages 57 to the chuck rotating motor. Motive fluid after passing through the chuck rotating motor exhausts through the passages 56 into the groove 57 whence it passes to the atmosphere through the passage 60 and arcual groove 96 on the valve plug to the exhaust discharge 93.

When the hole is to be blown, the valve is moved to the position shown by Fig. 15. Under these conditions, the exhaust discharge 93 is out of communication with the passages 67 and the live air passage 105 of the valve is brought into communication with one of the passages 67 which admits motive fluid thereto and discharges the same, through the passage 104 into the chuck casing whence it finds its way into the bore 100 of the steel. Under these conditions, the passages 90 and 91 are out of communication with the intake conduits leading to the percussive apparatus but obviously with the ordinary form of valve motion it will be sufficient if these passages remain in communication with the intake passages, providing the exhaust is closed. It, however, is desirable to control the motor by more or less throttling the intake and for this purpose the ports and passages are so constructed that the intake may be throttled to control the blow before the exhaust is closed. Such a position is shown by Fig. 18 in which it will be noted that the exhaust is open and that the admission to the passages 92 and 61 is throttled. By turning the valve slightly from this position the degree of throttling can be increased or diminished.

When the machine is to be placed out of operation, the valve is turned to the position illustrated by Fig. 17, which shows the

passage 59 supplying motive fluid closed. From this position the valve is progressively turned in the same direction to the positions illustrated by Fig. 15, in which the 5 hole is blown, that illustrated by Fig. 18 in which a small supply of air is admitted to operate the machine to strike a light blow, and finally that illustrated by Fig. 14, in which a full supply of air is admitted to the 10 hammer. The valve is moved from this last position in a reverse direction to throttle the hammer, blow the hole and finally to shut off the air.

It will be observed in all positions of the 15 valve the exhaust from the chuck rotating motor is not affected and the same irrespective of the position of the valve may be regulated or put out of operation by means of the throttle valve 98.

20 As has heretofore been pointed out, in the present embodiment of the invention the bearing blocks 32^b carry automatic lubricators and as the lubricator carried by each is similar, only one will be described. As 25 illustrated, formed transversely in the block is a cylindrical bore 106 which communicates with the exterior of the motor housing through an opening 107 in the motor housing member 28. Slidably mounted in the 30 bore I have shown a cylindrical plunger 108 which is provided with the intermediate grooves forming chambers 109 and 110. Connecting the oil reservoir provided by the 35 groove 51 with an intermediate portion of the bore 106 is a passage 111 and connecting the end of the bore with the groove 52 supplying the chuck rotating motor with 40 motive fluid is a passage 112. In the position shown by Fig. 2, oil is conducted from the oil reservoir by way of the passage 111 to the chamber 110 of the lubricator plunger and when the plunger is moved to the opposite end of its travel, this chamber is placed 45 in communication with the oil distributing passage 113 and the chamber 109 of the plunger brought into communication with the passage 111 and when the plunger again moves to the position shown by Fig. 2, the oil which has entered the latter is discharged 50 into the distributing passage 114 and the chamber 110 again filled. Herein the plunger is held in the position shown by Fig. 2 by means of a spring 115 interposed between 55 the end of the plunger and the plug 116 closing the bore 107. When motive fluid is admitted to the groove 52, the pressure thereof acting through the passage 112 on the end of the plunger overcomes the force of the 60 spring and moves the plunger to the opposite end of its stroke and when the supply to the groove 52 is interrupted, which results in the elimination of the pressure of the motive fluid on the end of the plunger, the spring moves the plunger to the position 65 shown by Fig. 2.

As illustrated, the passage 113 communicates with the passage 117 extending throughout the length of the shafts 25 and oil discharged into said passage is distributed by means of radial passages 118 establishing communication between said passage and the exterior of the shaft to the shaft and eccentric bearings. Oil which is admitted to the passage 114 finds its way through suitable connecting passages to 75 grooves 119 formed on the exterior surface of the cylinder extension 10 and serves to lubricate the bearing for the central rotor of the chuck motor. Some of the oil admitted to the passage 113 finds its way 80 around the rearward end of the shaft to lubricate the end bearing of the shaft and from this bearing into the interior of the chuck rotating motor and in a like manner some of the oil admitted to the groove 119 85 finds its way into the interior of the chuck rotating motor. The oil thus admitted into the interior of the chuck rotating motor serves to lubricate the gear teeth.

As will be understood by those skilled in 90 the art and as will be obvious a suitable filling orifice in communication with the exterior of the machine and provided with a suitable closure will be employed to replenish the oil supply for the groove 51. 95

The valve and other features herein shown are claimed in applicant's co-pending applications Serial No. 113,672, filed June 4, 1926 (which is a division of application Serial No. 386,868, filed June 5, 1920, on which 100 United States Patent 1,588,407 was granted to applicant June 15, 1926), and Serial No. 76,410, filed December 19, 1925 (which is a division of this application).

It is to be understood that although I 105 have described one specific embodiment of my invention for illustrative purposes extensive deviations from the same may be made without departing from the spirit of the invention.

Claims—

1. In a rock drill, a piston, a sectional casing for said piston, means for securing the sections of said casing in assembled relation, a chuck, a motor for rotating said 115 chuck, said motor carried by one of the piston casing sections and having a casing separate and removable from said piston casing, and means independent of said means for securing the piston casing sections in assembled relation for securing the motor casing to said piston casing section whereby the last named section can be removed with the motor as a unit.

2. In a rock drill, a piston having a hammer portion of larger diameter and an extension of smaller diameter, a casing section for said piston portion of large diameter, a separate casing section for said portion of smaller diameter, a chuck operating mo- 125 130

tor comprising a fluid operated member surrounding said separate casing section, a separate casing for said motor, means for securing said casing sections for said piston portions in non-rotatable relation, and means for securing said motor casing to said separate casing section whereby the latter may be removed with said motor as a unit.

3. In a rock drill, a hammer piston having an extension, a sectional casing for said piston comprising a separate section for said extension, said section having an exteriorly reduced portion, a chuck rotating motor comprising a rotor surrounding said portion, a separate casing for said motor surrounding said portion, means for securing said motor casing to said separate section, and separate means for securing in non-rotatable assembled relation the sections of said piston casing whereby said separate section for said extension and motor may be removed as a unit.

4. In a rock drill, a hammer piston having an extension, a sectional casing for said piston comprising a separate section for said extension, said section having an exteriorly reduced portion, a chuck rotating motor comprising a rotor surrounding said portion, means carried by said reduced portion for securing said motor casing to said separate section, and separate means for securing in non-rotatable assembled relation the sections of said piston casing whereby said separate section and motor may be removed as a unit.

5. In a rock drill, a hammer piston, a cylinder for said hammer piston having a main body portion, an end section for said cylinder forming a closure for said cylinder body portion and having a member projecting therefrom, a chuck rotating motor comprising a rotor journaled on said member, a casing for said motor surrounding said member and carried thereby, and means carried by said member for securing the motor casing thereto.

6. In a rock drill, a hammer piston, a cylinder for said hammer piston having a main body portion, an end section for said cylinder forming a closure for said cylinder body portion and having a member projecting therefrom, a chuck rotating motor comprising a rotor journaled on said member, a casing for said motor surrounding said member and carried thereby, and said member having a screw threaded portion carrying a nut for securing the motor casing to said member.

7. In a rock drill, a hammer piston, a cylinder for said hammer piston having a main body portion, an end section for said cylinder forming a closure for said cylinder body portion and having a member projecting therefrom, a chuck rotating motor comprising a rotor journaled on said member, a

casing for said motor surrounding said member and carried thereby, said member having a screw threaded portion carrying a nut for securing said motor casing to said member, and a cleansing fluid tube connected to said nut.

8. In a rock drill, a hammer piston, a cylinder for said hammer piston having a main body portion, an end section for said cylinder forming a closure for said cylinder body portion and having a member projecting therefrom, a chuck rotating motor comprising a rotor journaled on said member, a casing for said motor surrounding said member and carried thereby, a cleansing fluid conducting means, and said member having a screw threaded portion carrying a nut surrounding said conducting means for securing said casing to said member.

9. In a rock drill, a cylinder having a rearward extension of reduced diameter, a motor surrounding said extension, means for holding said motor and cylinder in assembled relation, feeding means for said cylinder, said feeding means comprising ears received in recesses in said cylinder, side bolts passing through said cylinder, said motor and ears, and said side bolts having their nuts at their rearward ends whereby said motor may be disassembled without removing said cylinder from said feeding mechanism.

10. A drilling machine having, in combination, a hammer cylinder comprising separate sections, at least three side bolts for securing said sections together, a member for supporting said cylinder, pairs of perforated ears on said member, and a pair only of said side bolts passing through the perforations of said ears, whereby said cylinder may be detached from said member while securing the sections of said cylinder together.

11. A rock drill, having in combination, a percussive motor comprising a sectional cylinder, a carriage for supporting said cylinder, a support slidably supporting said carriage, means for securing the sections of said cylinder together comprising a pair of side bolts at the side of said cylinder adjacent said carriage, longitudinally and transversely spaced ears on said carriage through which said side bolts extend, and other side bolts for securing said sections together.

12. A rock drill having, in combination, a sectional hammer cylinder having a plurality of side bolts for securing the sections thereof in assembled relation, a feeding mechanism including a carriage in side to side relation with said cylinder, and means securing said carriage to part only of said side bolts, whereby said cylinder may be detached from said carriage while securing said sections together.

13. A rock drill, having in combination,

a chuck, a hammer piston having a rearward extension, a cylinder for said hammer piston having a body and a separate rearward section, the latter forming a cylinder portion for said extension, said rearward section having a reduced exterior portion, a motor for driving said chuck having a rotor journalled on said reduced exterior portion and surrounding said rearward extension of said piston, a casing for said motor surrounding said reduced portion, means for securing said casing to said rearward section, and means independent of said first named means for securing said separate section to said cylinder.

14. A rock drill, having in combination, a chuck, a hammer piston having a rearward extension, a cylinder for said hammer piston having a body and a separate rearward section, the latter forming a cylinder portion for said extension, said rearward section having a reduced exterior portion, a motor for driving said chuck having a rotor journalled on said reduced exterior portion and surrounding said rearward extension of said piston, a casing for said motor surrounding said reduced portion, means for securing said casing to said rearward section, a feeding device for said cylinder having a slidably supported carriage, and common means independent of said means for securing said casing to said separate section for securing said separate section to the body of said cylinder and said cylinder to said carriage.

15. A rock drill, having in combination, a chuck, a hammer piston having a rearward extension, a cylinder for said hammer piston having a body and a separate rearward section, the latter forming a cylinder portion for said extension, said rearward section having a reduced exterior portion, a motor for driving said chuck having a rotor journalled on said reduced exterior portion and surrounding said rearward extension of said piston, a casing for said mo-

tor surrounding said reduced portion, means for securing said casing to said rearward section, a feeding device comprising relatively movable parts, side bolts independent of said means for securing said casing to said separate section for securing said separate section to the body of said cylinder, and spaced ears on one of said parts of said feeding device having openings through which said side bolts extend for securing said part to said cylinder.

16. A rock drill, having in combination, a cradle having a pair of longitudinally disposed ways, a cradle slidably supported in said ways, a percussive hammer having a sectional cylinder supported on said carriage, means for holding the sections of said cylinder in assembled relation comprising a pair of side bolts at the side of said cylinder adjacent said carriage, a pair of transversely spaced ears at each end of said carriage, recesses in said cylinder for receiving one or more of said pair of ears, said side bolts intersecting said recesses, and the portions of said ears received by said recesses having perforations through which said side bolts extend.

17. A rock drill, having in combination, a cradle having a pair of longitudinally disposed ways, a cradle slidably supported in said ways, a percussive hammer having a sectional cylinder supported on said carriage, means for holding the sections of said cylinder in assembled relation comprising a pair of side bolts at the side of said cylinder adjacent said carriage, a pair of transversely spaced ears at each end of said carriage, recesses in said cylinder for receiving one or more of said pair of ears, said side bolts intersecting said recesses, and the portions of said ears received by said recesses having means for locking said ears to said side bolts.

In testimony whereof, I have signed my name to this specification.

GEORGE H. GILMAN.

- a chuck, a hammer piston having a rearward extension, a cylinder for said hammer piston having a body and a separate rearward section, the latter forming a cylinder portion for said extension, said rearward section having a reduced exterior portion, a motor for driving said chuck having a rotor journalled on said reduced exterior portion and surrounding said rearward extension of said piston, a casing for said motor surrounding said reduced portion, means for securing said casing to said rearward section, and means independent of said first named means for securing said separate section to said cylinder.
14. A rock drill, having in combination, a chuck, a hammer piston having a rearward extension, a cylinder for said hammer piston having a body and a separate rearward section, the latter forming a cylinder portion for said extension, said rearward section having a reduced exterior portion, a motor for driving said chuck having a rotor journalled on said reduced exterior portion and surrounding said rearward extension of said piston, a casing for said motor surrounding said reduced portion, means for securing said casing to said rearward section, a feeding device for said cylinder having a slidably supported carriage, and common means independent of said means for securing said casing to said separate section for securing said separate section to the body of said cylinder and said cylinder to said carriage.
15. A rock drill, having in combination, a chuck, a hammer piston having a rearward extension, a cylinder for said hammer piston having a body and a separate rearward section, the latter forming a cylinder portion for said extension, said rearward section having a reduced exterior portion, a motor for driving said chuck having a rotor journalled on said reduced exterior portion and surrounding said rearward extension of said piston, a casing for said motor surrounding said reduced portion, means for securing said casing to said rearward section, a feeding device comprising relatively movable parts, side bolts independent of said means for securing said casing to said separate section for securing said separate section to the body of said cylinder, and spaced ears on one of said parts of said feeding device having openings through which said side bolts extend for securing said part to said cylinder.
16. A rock drill, having in combination, a cradle having a pair of longitudinally disposed ways, a cradle slidably supported in said ways, a percussive hammer having a sectional cylinder supported on said carriage, means for holding the sections of said cylinder in assembled relation comprising a pair of side bolts at the side of said cylinder adjacent said carriage, a pair of transversely spaced ears at each end of said carriage, recesses in said cylinder for receiving one or more of said pair of ears, said side bolts intersecting said recesses, and the portions of said ears received by said recesses having perforations through which said side bolts extend.
17. A rock drill, having in combination, a cradle having a pair of longitudinally disposed ways, a cradle slidably supported in said ways, a percussive hammer having a sectional cylinder supported on said carriage, means for holding the sections of said cylinder in assembled relation comprising a pair of side bolts at the side of said cylinder adjacent said carriage, a pair of transversely spaced ears at each end of said carriage, recesses in said cylinder for receiving one or more of said pair of ears, said side bolts intersecting said recesses, and the portions of said ears received by said recesses having means for locking said ears to said side bolts.
- In testimony whereof, I have signed my name to this specification.
- GEORGE H. GILMAN.

CERTIFICATE OF CORRECTION.

Patent No. 1,658,330.

Granted February 7, 1928, to

GEORGE H. GILMAN.

It is hereby certified that error appears in the printed specification of the above numbered patent requiring correction as follows: Page 6, lines 125 and 126, claim 2, strike out the word "hammer" and insert the same before the word piston in line 125; and that the said Letters Patent should be read with this correction therein that the same may conform to the record of the case in the Patent Office.

Signed and sealed this 3rd day of April, A. D. 1928.

M. J. Moore,
Acting Commissioner of Patents
